CLAIM

The ornamental design for a storage rack for a warehouse as shown and described.

DESCRIPTION

FIG. 1 is a front view of a storage rack for a warehouse showing our new design;

FIG. 2 is a back view thereof;

FIG. 3 is a right side view thereof;

FIG. 4 is a left side view thereof; and

FIG. 5 is a top view thereof;

(Continued)

FIG. 6 is a bottom view thereof; and,
FIG. 7 is a perspective view thereof.

1 Claim, 7 Drawing Sheets
